US00D985595S

(12) **United States Design Patent** (10) Patent No.: **US D985,595 S**
Grail et al. (45) Date of Patent: ** May 9, 2023

(54) **DISPLAY SYSTEM OR PORTION THEREOF
WITH A VIRTUAL THREE-DIMENSIONAL
ANIMATED GRAPHICAL USER INTERFACE**

(71) Applicant: **SAP SE**, Walldorf (DE)

(72) Inventors: **Christian Grail**, Zuzenhausen (DE); **Joachim Fiess**, Karlsruhe (DE); **Tatjana Borovikov**, Pfungstadt (DE); **Judith Schneider**, Sulzfeld (DE); **Manfred Johann Pauli**, Bad Schönborn (DE); **Gisbert Loff**, Hockenheim (DE); **Hanswerner Dreissigacker**, Ludwigshafen (DE); **Klaus Herter**, Leimen (DE); **Hans-Juergen Richstein**, Rauenberg (DE); **Ian Robert Taylor**, Mannheim (DE)

(73) Assignee: **SAP SE**, Walldorf (DE)

(**) Term: **15 Years**

(21) Appl. No.: **29/845,904**

(22) Filed: **Jul. 12, 2022**

Related U.S. Application Data

(63) Continuation of application No. 29/718,129, filed on Dec. 20, 2019, now Pat. No. Des. 959,447.

CLAIM

The ornamental design for a display system or portion thereof with a virtual three-dimensional animated graphical user interface, as shown and described.

DESCRIPTION

FIG. 1 shows a display system or portion thereof with a virtual three-dimensional animated graphical user interface showing a first image of the claimed design;

FIG. 2 shows a second image thereof; and,

FIG. 3 shows a third image thereof.

The outermost broken lines in the figures show a display system or portion thereof, and form no part of the claimed design. The other broken lines in the figures show portions of the virtual three-dimensional animated graphical user interface that form no part of the claimed design.

The shaded claimed portions in the figures show a contrast in appearance with the non-shaded claimed portions.

The appearance of the animated image sequentially transitions between the images shown in FIGS. 1-3. The process or period in which one image transitions to another forms no part of the claimed design.
